(57) **CLAIM**

The ornamental design for a fragrance emanation device with car vent clip, as shown and described.

DESCRIPTION

FIG. 1 is a front perspective view of a fragrance emanation device with car vent clip according to our new and ornamental design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front perspective view of the fragrance emanation device with car vent clip of FIG. 1 in an open-body configuration; and,

FIG. 9 is a right side elevation view of the fragrance emanation device with car vent clip in the open-body configuration, the left side elevation view thereof being a mirror image.

The broken lines illustrate portions of the fragrance emanation device with car vent clip that form no part of the claim.

1 Claim, 9 Drawing Sheets
